FLASH ANALYZER

Bernard M. Jaffe, New York, N. Y.

Application June 9, 1945, Serial No. 598,484

2 Claims. (Cl. 177—352)

(Granted under the act of March 3, 1883, as
amended April 30, 1928; 370 O. G. 757)

1

The invention described herein may be manufactured and used by or for the Government for governmental purposes, without the payment to me of any royalty thereon.

This invention relates to a flash azimuth locator, or a device capable of determining the azimuth of a distant, instantaneous flash, such as flash due to firing of an enemy gun. More particularly the invention relates to an improvement in a flash azimuth locator disclosed in a patent application of Morris Keiser, et al., S. N. 599,297, filed on June 13, 1945, and titled "Azimuth Locator," the improvement residing in equipping the flash azimuth locator with a recording spectrograph.

It is well known in the art of interior ballistics that the desired muzzle velocities of large projectiles can not be attained without flash with the known compositions of the propellant powders and flash-reducing agents. The resulting flashes are visible with a naked eye at night, and with the flash azimuth locator—in the daytime. These flashes alone, or together with some additional apparatus not disclosed in this application, may be used for determining either the azimuth alone or the exact location, i. e., both azimuth and range, of a flash source. Since the location of guns by their flashes has been practiced in the past and the enemy is always on guard against such contingency, there are occasions when the enemy resorts to setting off simulated "gun flashes" to confuse the opponent. It has been discovered that effective simulation of the real gun flashes is difficult, if the flashes are analyzed spectroscopically. An actual gun-flash will exhibit, when viewed in a spectroscope, a line spectrum superimposed on a continuous spectrum; the line spectrum is due to the burning gases and the continuous spectrum is due to incandescent carbon particles. Since it is difficult to simulate the line spectrum of the actual gun flash by some artificial means, the simulated flashes may be detected and separated from the real gun-flashes by means of the recording flash spectrograph.

It is therefore an object of this invention to provide a flash azimuth locator capable of distinguishing the desired distant flashes from the simulated flashes in the process of determining the azimuth of the desired flashes by presenting the flashes in the form of characteristic line spectra.

An additional object of this invention is to provide a spectroscope and collimator system provided with instrumentalities for limiting the light entering the spectroscope to that which comes only from a source substantially along the optical axis of the collimator so that only the

2

flashes along the previously determined azimuth of the flash may have any effect on the flash azimuth recorder.

Still another object of this invention is to provide a spectrograph in which the optical axes of the collimator and of the telescope are parallel.

These and other features of the invention will be more clearly understood from the following detailed description and the accompanying drawing in which,

- 10 Figure 1 is block diagram of the flash azimuth locator provided with a spectrograph,
15 Figure 2 is a plan view of the spectrograph used in connection with the locator.
20 Figure 3 is a typical candlepower-vs.-time curve of a flash.
Figure 4 illustrates oscillosograms of illuminations scanned by a scanning drum, and
25 Figure 5 illustrates an oscillosogram of an illumination spectrum scanned by a scanning drum with a spectrograph before it.

Referring to Fig. 1, an optical telescope system illustrated diagrammatically as a lens 10, is pointed with its optical axis in the direction 30 of the expected flash. The telescope forms a real image of the flash, and of a region of space which it is desired to examine, in the plane of rectangular aperture 13 provided in an aperture plate 14. Plate 14 is mounted directly in front of a scanning cylinder 12 which consists of a slotted drum having equidistant slots 11. The scanning drum is mounted on a vertical shaft and scans the aperture from one side-edge of the aperture to the other with the narrow vertical slots. In one embodiment of the invention, the horizontal slot dimension, i. e., in the direction of scanning, has an angular slot width of 1 mil since this is the desired limit of angular resolution of the locator. The optical axis of the telescope is coaxial 35 with the normal axis of the aperture and is in the radial relationship to the cylinder. The aperture is the field stop of the system, and its size, together with the constants of the optical system, determine the angular field of view of the instrument, which in a typical case is 60 mils by 60 mils. It is preferable to make the diagonal line joining the corners of the square aperture equal to the diameter of the image of the field of view of the telescope produced by the latter 40 in the plane of aperture 13; this is done in order to utilize as much of the image as possible. Thus, the dimensions of the aperture depend upon the focal length of the lens system used in the telescope and the desired angle of acceptance of this 45 lens system. The light leaving the aperture is sufficiently divergent so that a photo-electric cell 15 placed immediately behind the drum, receives a sufficiently defocussed light to avoid complete

obstruction of any image by the anode of the cell and the concomitant formation of the blind spots. The scanned gun flash is converted into electrical pulses which are impressed on a recording amplifier 16, the output of which is connected through a switch 17 to a recording magnetic head 18 which is positioned in recording relationship with respect to a magnetic tape 19. The distance between the center lines 420 and 421, Fig. 4, of the scanning slots 11 is preferably equal to the horizontal dimension of the aperture, as illustrated in Fig. 4, where two scanning slits 11 of scanning drum 12 are drawn so that their center lines coincide with the side-edges 422 and 423 of aperture 13. This is done to insure that the successive scanning cycles are continuous, without either excessive overlap or blank space, as illustrated at 400 through 403 in Fig. 4 where the cross-hatched portions illustrate the signal due to general background illumination present in the field of view of the telescope 10 while 404, 405, and 406 are the light signals produced by flash 300, when its image in aperture 13 is scanned by slits 11. It may be noticed that in Fig. 4 the background illumination never drops down to zero level indicated by a reference line 407, which is due to the fact that when the lagging edge of one slot leaves the aperture, the succeeding scanning slot is in full view of the aperture. This being the case, there exists a slight overlap of the two successive slots and, as a consequence, the photo-electric cell is never cut off completely from the aperture. Any excessive overlap of the two adjacent slots with the aperture must be avoided since it would result in confusion and jumbling of information from two parts of the field; blank spaces are not positively objectionable in that they do not result in the confusion of intelligence on the oscilloscope screen but they do limit or decrease the resolution of the total system by decreasing the portion of the frame devoted to useful information. These slots in a typical case pass across the aperture, i. e., scan the field of view, at a rate of not less than 100 times per second. The reason for this rate of scanning will become more apparent on later consideration of the characteristics of the flash, and especially of its duration. Each scansion is in many respects equivalent to one frame of a motion picture film; the terminology of this analogy will be used in several instances in this disclosure. The scanning slotted drum 12, and the magnetic tape are placed on the same vertical shaft 20 which is connected to a motor 21. The tape is mounted concentric with and rigidly attached either to the upper or lower edge of the periphery of the scanning drum, the two being rigidly connected to shaft 20 so that they are rotated at the same speed by motor 21.

An oscillator 22 is connected through a switch 23 to an erasing head 24 which is positioned on the magnetic tape in front of the recording head. Switches 17 and 23 are ganged switches which are opened by the operator immediately after the observation of the flash with the result that the record of the flash is retained on magnetic tape 19 because of the time reservoir provided by the tape. This time reservoir is in the order of 1 second, i. e., if the magnetic tape is mounted upon the scanning cylinder, the cylinder will be driven by the motor at 1 revolution per second. This time reservoir is ample for allowing the operator to disconnect the recording and erasing heads after observing the occurrence of the flash

and before the recorded signal is erased by the erasing head.

After the flash has been recorded on magnetic tape 19 and the erasing and reproducing heads disconnected, the recorded signal is viewed on the screen of an oscilloscope 25, the vertical deflection plates of which are connected through mixer 26 and a reproducing amplifier 27 to reproducing heads 28 and 29, which are connected in series through a switch 30, which is in its upper position during this portion of the reproducing cycle, but in phase-opposition for eliminating the extraneous background illuminations which may be also present as an additional recorded signal on the magnetic tape. This background signal is illustrated at 400 through 403. The reproducing heads 28 and 29 are spaced with respect to each other, along the magnetic tape so that while the first head 28 is playing back the background signal 400 plus the recorded pulse 404, the other head is playing back the signal due to the background noise 403 alone. The pick-up heads are adjusted to have the same sensitivity so that if the background signal has not changed appreciably during the short time interval required for the tape to travel from the first to the second pick-up head, the background signal is cancelled out and only the signals 404, 405, and 406 due to the gun flash are impressed on the reproducing amplifier 27 and the vertical deflection plates of oscilloscope 25. The two pick-up heads are preferably placed at least 3 frames apart and the scanning cylinder is driven at such a rate that the duration of a typical gun flash shall be scanned in 3 frames, as is disclosed more fully in connection with Fig. 4. The obliterating, recording and pick-up heads are all mounted on a base plate which itself is mounted independently of the scanning disc 12 on a tripod supporting the flash azimuth locator. The reproducing heads 28 and 29 are provided with the mechanical means for shifting their position with respect to the magnetic tape during the preliminary adjustment of the locator which results in shifting of the reproduced signal on the screen of oscilloscope 25 with respect to the marker signals or scale gratings 21 also appearing on the same screen. Once this adjustment has been accomplished, the heads are locked in the desired position, and remain stationary from then on. The sweep circuit 32 of the oscilloscope is synchronized by means of a commutator 31 mounted on shaft 20 and a commutator brush 33 with the scanning of the aperture by slots 11 so that a saw-tooth 410, Fig. 4 voltage is generated once during each scanning period in which slot 11 scans aperture 13. Mixer 26 is also connected to a reference marker amplifier 34 which is connected to a synchronizing brush 35, and a commutator 36 connected through step-up ratio gears 37 and 38 to shaft 20 and motor 21.

For an understanding of the rate of scanning and synchronization reference is made to Figs. 3 and 4. In Fig. 3 the illustrated curve 300 represents the intensity-of-flash-vs.-time curve of a typical gun flash. The gun flash lasts for approximately 0.03 second and may be of the order of 100,000 candle power. In Fig. 4, 19 represents the magnetic tape with the reproducing heads 28 and 29 placed in the proper position with respect to the tape. The irregular cross-hatched curves 400 through 403 represent the signals recorded on tape 19 due to the light intensity of the background or the previously mentioned background signal, and 404, 405, and 406 represent the super-

imposed flash signals also recorded on the tape. The first portion 404 of the recorded flash happened to coincide with the maximum candle-power of flash 300 while the remaining portions 405 and 406 reproduce the lower intensities of the flash. It is desirable to have the flash scanned with at least three slots to avoid missing the flash altogether or reproducing only the weaker portions of the illumination. When three slots scan the flash, the scans being one second apart, one of them is bound to coincide with a fairly high intensity of illumination on the curve, which is apparent from the examination of Figs. 3 and 4. If the duration of the gun flash is in the order of 0.03 second and the drum is driven at such a speed that approximately 3 frames scan the field of view during the duration of the flash, the 4th frame will record only the background noise. Therefore, magnetic head 29, placed 3 frames behind head 28, as illustrated in Fig. 4, will impress the background signal 403 in phase-opposition to the background signal 400 reproduced by head 28, and since the two heads have equal sensitivities, or reasonably so, there will be substantially complete cancellation of the background signal with the result that only the flash signals 404, 405, and 406 will be reproduced as an image 39 on the oscilloscope screen in a manner illustrated in Fig. 1. The linear portion of the saw-tooth voltage 410 has approximately the same period as the time required for scanning with one slot, i. e., 0.01 second. If it is desired to scan 3 frames per flash, the scanning cylinder may have 100 evenly spaced slots 11 and be driven at 1 revolution per second. Fig. 4 also illustrates, with the aid of the vertical dotted lines, the synchronization of the magnetic tape, sweep voltage, and the instantaneous position of slots 11 with respect to aperture 13, and arrow 412 and 413 indicate the direction of rotation of drum 12 and tape 19. Examination of Fig. 4 and the relative positions of the elements illustrated in Fig. 4 indicates that the sweep wave 410 must begin at the instant when head 28 begins to reproduce signal 400, which during the recording cycle corresponds to the instant when the lagging edge of slit 11 reaches the side-edge 422 or 423 of aperture 13. At this instant the sweep-controlling brush 33 leaves the shorting segment on commutator 31, this shorting segment discharging the saw-tooth generating condenser in the interim of time required for slit 11 to travel 0.5 mil across aperture 13, i. e., half of the slits' width. When the synchronization of the reproduction and of the saw-tooth generator is as described above, the position of pulse 39 on the oscilloscope screen depends upon the azimuth of the flash since the azimuth of the flash determines the position of its images 404, 405, and 406 within aperture 13, and the remaining apparatus, because of the illustrated timing of the saw-tooth wave 410 with respect to tape 19, and especially the signals recorded on the tape with the aid of the scanning slots 11, simply transfers the images of the flash produced at the aperture onto the oscilloscope screen. Thus the azimuth of the flash determines the position of image 39 on the oscilloscope screen and saw-tooth wave 410 acts as a timing locus for positioning this image in proper azimuth relationship on the screen. The markers 27 are used for determining the actual azimuth reading of the azimuth locator by determining the position of image 39 with respect to the ends of the sweep line 41, Fig. 1, the ends of the sweep line on the screen representing the edges 422 and 423 of aperture 13.

After the azimuth of the recorded flash has been determined in accordance with the described procedure, the optical axis 9 of the locator is rotated, if necessary, so as to point it directly at the source of flash by turning the locator on its vertical axis secured to the tripod an angle equal to the previously determined azimuth angle. With such orientation of the azimuth locator with respect to the source of flash, the next succeeding flash from the same source would be reproduced directly in the center of the screen of oscilloscope 25. Telescope 10, and spectrograph 40 are mounted on a rotatable bracket 42 which can be rotated around the vertical shaft 20. With the optical axis of the locator, which corresponds to a line normal to the plane of aperture 13 and passing through the center of aperture 13, pointing directly at the source of flash, telescope 10 is swung, 15 with the aid of bracket 42, away from its normal position which is in line with the optical axis of the locator, and spectrograph 40 is swung into the position previously occupied by telescope 10 so that the optical axis 43 of the image-forming lens, 20 or telescope, of the spectrograph now coincides with the position previously occupied by the optical axis 9 of the telescope. Thus the next flash, coming from the same source, will be intercepted by the same flash azimuth locator in 25 which its telescope 10 has been replaced by spectrograph 40, and as a result the flash signal recorded on the same magnetic tape 19 will include a signal produced by the incandescent carbon particles and a series of signals due to the line 30 spectrum of the flash. The spectrum is produced by the burning gases causing the flash. For viewing the signals recorded on the magnetic tape, switch 30 is used in its lower position so that only 35 reproducing head 28 picks up the signals from the magnetic tape. Since the spectral images completely embrace the entire field of view, the background noise is substantially eliminated by the received gun flash and therefore the use of background noise eliminating head 29 is not required. 40 The signal that appears on the oscilloscope screen is illustrated in Fig. 5; it consists of an approximately uniformly illuminated field 500 and a series of spectral lines 501, 502, and 503 which are used for identifying the flash and for determining 45 whether it is a true gun flash or a simulated flash. Since the simulated flash will have different spectral distribution as compared to the spectral distribution of the true flash, comparison of the outline illustrated in Fig. 5 with the known outline 50 of the true gun flash will identify the nature of the intercepted flash. If the two match each other, the recorded flash is the true gun flash. When this is not the case, the recorded flash is 55 a simulated flash. 60 Fig. 2 discloses the spectrograph on a magnified scale. It consists of an image-forming telescope illustrated diagrammatically as a lens 202 which is positioned in front of an aperture plate 200 provided with an aperture 201. The image of the 65 flash is produced in the plane of aperture 201 and is then intercepted by a collimator 204 which converts the intercepted beam of light 210 into a parallel beam of light 205. This is intercepted by a mirror 206 which deflects beam 205 so that it enters a light-resolving prism 207 which resolves the light into the individual wave length components 208, 209, 210, etc. These are intercepted by an image-forming telescope illustrated as a 70 condenser lens 212 which forms an image 214 of the spectrum at aperture 13 and it is this spec- 75

trum that is scanned by disc 12 and photo-electric cell 15. The spectrograph is provided with aperture 201 and aperture member 200 so that only the source of light directly in line with the optical axis 9 of the locator may have any effect on the photo-electric cell, the side flashes, such as flashes 216 and 217, having no effect on the scanning system since all illumination produced by these flashes is intercepted by the aperture member 200, as illustrated in the figure. The light-reflecting mirror 206 is mounted on a bracket 218, and the bracket is supported by a round pin 220; the pin in turn is supported by an outer casing 222 of the spectrograph. The axis of pin 220 is parallel to edges 224, 225, and 226 of the prism, and the plane of mirror 206 is parallel to the axis of pin 220. The purpose of mirror 206 is for making the optical axis 228 of telescope 202 and collimator 204 parallel to the optical axis 230 of telescope 212. Accordingly the angular position of the mirror with respect to the beam of light 205 is dictated by this parallel relationship of the two optical axes. The light-reflecting mirror 206 is placed between the collimator lens 204 and prism 207. The parallel relationship of the optical axes 228 and 230 may be also accomplished by placing mirror 206 between prism 207 and telescope 212, as illustrated in Fig. 1, where spectrograph 40 is constructed with the reflecting mirror placed between the prism and the spectrum-focussing telescope.

The invention thus discloses an azimuth locator provided with two optical systems, one being telescope 10, and the other spectrograph 40, telescope 10 is used for pointing optical axis of the azimuth locator directly at the source of flash while spectrograph 40 is used for producing the spectrum of a subsequent flash from the same source. The spectrum is recorded on a magnetic tape and is reproduced during the reproducing cycle of the system as a series of spectral lines 501-503. These are compared with the known spectrum of a real gun flash, this comparison revealing the fact whether the recorded flashes are real flashes or simulated flashes.

The spectrograph provided for obtaining the aforementioned results includes aperture plate 200 for restricting the field of view of the spectrograph to a very small angle of acceptance so that the side flashes or background illumination have no appreciable effect on the flash azimuth locator. The spectrograph is also provided with a reflecting mirror for changing within the spectrograph, the direction of the intercepted light so as to make the optical axis of condenser 202 parallel to the optical axis of condenser 212. This is necessary for pointing the spectrograph directly at the object producing the flash subsequent to pointing the optical axis of the azimuth locator directly at the desired object. By making the two optical axes of the spectrograph parallel, it becomes possible to point the spectrograph in the desired direction by merely rotating it on bracket 42. Rotation of bracket 42 aligns the optical axis 230 of the telescope with the optical axis 9 of the azimuth locator and since the optical axis 228 of telescope 202 is made parallel to the optical axes 230 and 9, the telescope lens 202 will be pointing directly at the object producing the flashes under investigation.

It is believed that the construction and operation of the flash azimuth locator and spectrograph disclosed in this specification, as well as the advantages thereof, will be apparent from the foregoing description. It should be under-

stood therefore that while the invention has been illustrated and described in several preferred forms, reasonable changes and modifications may be made by those skilled in the art without departing from the spirit of the invention as sought to be defined in the following claims.

I claim:

1. A real gun flash detector comprising means to resolve a flash into its spectrum, periodic means to scan said spectrum, a magnetic tape recorder to record the scanned spectrum, a reproducing head associated with said recorder to transduce said magnetic record into voltage variations, a cathode ray oscilloscope having beam control means, means to generate a sweep control voltage in synchronism with said periodic means, means to impress said sweep control voltage upon said beam control means to deflect said beam along a time base axis, and means to impress the output of said reproducing head upon said beam control and to thereby deflect said beam along another axis.

2. A real gun flash detector including an optical field stop, means to resolve a flash into its spectrum, an optical system to form an image of said spectrum in the plane of said field stop, a photoelectric cell spaced opposite said optical field stop, means between said photoelectric cell and said field stop to periodically scan said field stop whereby said photoelectric cell output varies in accordance with the light intensity of said optical field stop, a magnetic recorder connected to said photoelectric cell output, a reproducing head associated with said magnetic recorder, a cathode ray oscilloscope having beam deflection means, means to generate a sweep voltage in synchronism with said periodic scan means, means to impress said sweep voltage upon said beam deflection means to deflect said beam along a time base axis, and means to impress said reproducing head output upon said beam deflection means to deflect said beam along another axis.
